CLAIM

The ornamental design for an interlockable industrial support mat with steel fingers and forklift slots as shown and described.

DESCRIPTION

FIG. 1 is an orthogonal view from the top of the interlockable industrial support mat with steel fingers and forklift slots showing the claimed design;

FIG. 2 is an orthogonal view from the bottom of the claimed design;

FIG. 3 is a top view of the claimed design;

FIG. 4 is a bottom view of the claimed design;

FIG. 5 is a front elevation view of the claimed design;

FIG. 6 is a rear elevation view of the claimed design;

FIG. 7 is a left side view of the claimed design; and,

FIG. 8 is a right side view of the claimed design.

1 Claim, 5 Drawing Sheets
